Kenneth R. Lung, Dayton, Ohio, assignor to The Dayton Pump and Manufacturing Company, Dayton, Ohio, a corporation of Ohio

Application July 10, 1953, Serial No. 25,878

Term of patent 14 years

(Cl. D65—1)

To all whom it may concern:

Be it known that I, Kenneth R. Lung, a citizen of the United States, resident in Dayton, Montgomery County, State of Ohio, have invented a new, original, and ornamental Design for a Combined Motor and Pump, of which the following is a specification, reference being had to the accompanying drawings, forming a part thereof, wherein:

Figure 1 is a side view of a combined motor and pump embodying my new design;

Figure 2 is a view looking down on top of Figure 1;

Figure 3 is a view looking in from the right side of Figure 1; and

Figure 4 is an end view looking in from the bottom of Figure 3.

I claim:

The ornamental design for a combined motor and pump, substantially as shown.
